DESIGN FOR DRESS-TRIMMING.

Design No. **11,178**, dated May 6, 1879# UNITED STATES PATENT OFFICE

JULIUS GERSON, OF NEW YORK, N. Y., ASSIGNOR TO THE DUNNELL MANUFACTURING COMPANY, OF PAWTUCKET, RHODE ISLAND.

DESIGN FOR DRESS-TRIMMING.

Specification forming part of Design No. **11,178**, dated May 6, 1879; application filed March 1, 1879.
[Term of patent 3½ years.]

To all whom it may concern:

Be it known that I, JULIUS GERSON, of New York, in the county of New York and State of New York, have invented a new and useful Design for Printed Trimmings for Dress-Goods, &c.; and I do hereby declare that the following specification, taken in connection with the accompanying illustration, forming a part of the same, is a full, clear, and exact description thereof:

The novel design hereinafter described consists of a printed representation of a combination-trimming for ornamenting dress-goods, &c., the said design having the following features.

A represents a portion of a pattern of dress or other goods composed of vertical stripes, the said portion being bounded on the lower edge by a broad line, *a*, in imitation of binding. At some distance above the line *a* is arranged a transverse flounce, *B*, of coarse box-plaiting, the goods being striped and represented as cut diagonally. This flounce is apparently placed upon the surface of the goods, and is bounded on the lower edge by an irregular line, *b*, in imitation of binding, and the under plaits are shaded to retire them into a proper position, the character of the line *b* assisting in producing the desired effect.

The flounce *B* is headed by an ornamental band, *C*, which is surmounted by inverted box-plaiting *D*, finer than that composing the flounce *B*, the plaiting *D* being bounded upon its upper edge by a broken line, *d*, in imitation of binding, and the under plaits being shaded, as above described.

The fabric may be printed in any preferred variety or combination of colors for giving a desirable effect to the design above described, the characteristic feature of which is a printed representation of bound box-plaited trimmings separated by an ornamental band, in combination with a portion of a pattern of dress or other goods, represented as bound on its lower edge.

Having described my invention, what I claim, and desire to secure by Letters Patent, is—

The design for printed trimmings for dress-goods embodying the representation of a transverse box-plaited flounce, a head-band, and a line of box-plaiting above the band, substantially as herein described, and shown in the accompanying illustration.

JULIUS GERSON.
